(57) **CLAIM**

The ornamental design for a locking cap, as shown and described.

DESCRIPTION

FIG. 1 is a top perspective view of a locking cap in an open position, showing my new design;

FIG. 2 is a front elevational view thereof, illustrated in a closed position;

FIG. 3 is a side elevational view thereof; and,

FIG. 4 is a front elevational view thereof, showing an exemplary bottle in dashed lines.

Subject matter illustrated in dashed lines depicts environmental subject matter only and does not form part of the claim.
